STORM WINDOW AND SCREEN ASSEMBLY

Joseph Sylvan, Berkley, Mich.

Application October 31, 1949, Serial No. 124,622

4 Claims. (Cl. 160—90)

1

This invention relates to an improved window assembly.

An object is to provide a storm sash and screen assembly so designed as to constitute a self-contained unit including two window sashes and a screen sash and wherein the screen sash may be stored within the assembly overlying one of the window sashes or one of the window sashes may be stored within the assembly overlying the other window sash.

Another object is to provide a storm sash and screen assembly of simple construction and which occupies a minimum thickness and may be formed of sheet metal and wherein two window sashes and a screen sash are included within the assembly and the several sashes may be quickly and easily removed from the inside of the window.

An important feature is the provision in a window assembly of the character described of a pair of complementary jamb members provided with two pair of opposed complementary lower guide channels each adapted to receive a sash and wherein the outer side wall of the outer lower guide channel extends upwardly throughout the upper half of the window assembly to form an outer guide wall for the upper sash. The upper sash may be held within the assembly by frictional engagement at the top within a header channel and supporting engagement at the bottom upon one of the lower sashes.

Another meritorious feature is the provision in a window assembly having jamb members and upper and lower sashes as described of an upper sash having a channel shaped bottom rail adapted to receive the top rail of the lower sash to support the upper sash thereupon; such bottom rail also defines an inwardly offset upwardly open channel adapted to receive the bottom rail of another elevated sash to maintain the same in elevated overlying relationship therewith; such offset upwardly open channel is adapted to receive an interengaging downwardly open top rail channel of a lower sash.

More specifically, the window assembly includes a pair of jamb members provided with two complementary pair of lower guide channels one an outer guide channel and the other an inner guide channel and wherein the outer wall of the outer lower guide channel extends upwardly throughout the upper portion of the jamb members and wherein a lower screen sash may be disposed within the outer lower guide channel and a lower window sash may be disposed within the inner lower guide channel and wherein an upper window sash may be disposed between the jamb members above the screen resting upon the screen and engaged therewith against relative lateral displacement and wherein a header channel is provided to receive the top rail of the upper

2

sash when such sash is disposed upon the screen.

Other objects, advantages and meritorious features will more fully appear from the following specification, claims, and accompanying drawings, wherein:

Fig. 1 is an elevation of the window structure embodying this invention;

Fig. 2 is a vertical sectional view partly broken away being a perspective of a part of the window assembly;

Fig. 3 is a horizontal sectional view taken on the line 3—3 of Fig. 1;

Fig. 4 is a fragmentary perspective of the lower part of the window assembly as shown in Fig. 2 but with the sash removed;

Fig. 5 is a perspective similar to that shown in Fig. 2 but showing the two window sashes in the elevated position; and

Fig. 6 is a fragmentary perspective of a character similar to Fig. 5 but showing one of the window sashes reversed end for end as compared with Fig. 5.

This window assembly is designed primarily to be formed from sheet metal. It may be formed of other suitable material. In the drawings two upright opposed complementary jamb members are indicated by the numeral 10. They are connected at the top by a header 12 and at the bottom by a sill member 14. Each jamb member may be formed of sheet metal bent, as shown particularly in Fig. 2, into channel shape. The channel may be received over a wood jamb member 18, as shown in Fig. 2. Each jamb member is provided with a sash guide channel side wall portion 20. This side wall portion 20 may be formed by a fold in the metal, as shown particularly in Figs. 2, 3 and 4. This side wall 20 forms the outer wall of the outer guide channel for the sliding sash which is mounted between the jamb members.

The sill member 14 which connects the jamb members at the bottom is shown particularly in Figs. 2, 4 and 5 as shaped to provide a downwardly open channel portion which may, if desired, be seated over a wood strip 22. Such channel, however, might be closed at the bottom with a metal strip. This sill portion 14 is provided with an inner side wall ledge 24, as shown particularly in Figs. 2, 4 and 5. This inner side wall ledge constitutes an abutment at the bottom against which a lower window sash may rest and be retained.

The header member 12 which connects the jamb members at the top may be formed of sheet metal folded upon itself to exhibit an outer side wall portion 26, intermediate wall portion 28, and an inner wall portion 30, all as shown particularly in Figs. 2, 5 and 6. The space between the wall portions 26 and 28 constitutes an outer header channel. The space between the wall portions 28 and 30 constitutes an inner header

channel. These header channels are adapted to receive the top rails of upper sash elements and frictionally engage them. They serve to help support the upper sash elements by such frictional engagement. These header channels have such a depth that the upper sash elements may occupy a closed position, as shown in Figs. 2, 5 and 6, and there still will be space above the top rails of the sash to permit elevation of the upper sash within the header channels 10 for purposes hereinafter set forth.

Each jamb member 10 is provided with a channel strip 32, as shown particularly in Fig. 4. This channel strip 32 may be secured by rails or the like 34 directly to the wood backing 18, Fig. 3. This channel strip 32 extends along the bottom half of each jamb member spaced inwardly from the side wall 20 so that the outer wall 36 of the channel member 32 forms with the side wall 20 an outer lower runway or guide. This side wall portion 36 is bent inwardly providing a marginal flange 38, as shown particularly in Fig. 4. Spaced between the edge of this marginal flange 38 and the inner side wall of the channel 32 is an inner lower channel guide, as shown particularly in Figs. 2 and 5.

This window assembly is adapted to accommodate two window sashes and a screen sash and to provide for permanent storage of these three sashes within the assembly so that it becomes a year-round assembly as hereinafter set forth.

In Fig. 2 there is shown an upper window sash indicated by the letter "U" and a lower window sash indicated by the letter "L," and a screen sash indicated by the letter "S." The lower window sash is disposed within the channel 32 within the lower half of the window. The upper window sash is disposed between the jamb members with its top rail received within the outer header channel and with its side rails resting against the outer channel guide walls 20 and with its bottom rail 40 superimposing the top rail of the screen sash "S."

The bottom rail 40 is shown as formed of sheet metal shaped so as to exhibit a downwardly open channel 42. This downwardly open channel 42 is shown in Fig. 2 as receiving a top rail of the screen "S." It fits thereover. This engagement of the bottom rail of the upper sash with the top rail of the screen and the engagement of the top rail of the upper sash within the outer channel of the header holds the upper sash against any lateral displacement. The upper sash is also supported in the elevated position.

The screen which is shown as resting at the bottom upon the sill member 14 and resting throughout its height against the outer channel wall 20 is held thereby in place and in the position shown in Fig. 2 is in what might be termed a "stored position" alongside the window sash.

The lower window sash mounted within the inner channels 32 between the jamb members is provided with top and bottom rails of a particular construction for the purpose hereinafter described.

The bottom rail 40 of the upper sash exhibits in addition to the downwardly open channel 42 an upwardly open inwardly offset channel 46, note Figs. 2, 5 and 6.

In Fig. 2 the lower sash is shown as having a top rail so folded upon itself as to exhibit an outwardly laterally offset downwardly open channel 50 which interlocks within the channel 46 of the bottom rail of the upper sash, as shown in such figure. This interlocking engagement 75

forms a tight seal between the two sashes. The bottom rail of the lower sash shown in Fig. 2 is so shaped as to provide an inwardly laterally offset downwardly open channel part 52 which, as shown in Fig. 2, may serve as a handle.

If it is desired to employ the window assembly with the lower window space opened and closed merely by the screen, the lower window may be lifted out of the retaining channels 52. These channels extend only throughout the lower half of the jamb members as shown. When lifted out of the lower channels 52, the lower window may be placed alongside of the upper window with its top rail received within the inner channel of the header as shown in Fig. 5, and with its bottom rail seated within the channel 46 of the upper sash, as shown in Fig. 5. When so seated the channel part 52 overhangs the top of the screen so that the screen can be elevated only a very limited distance. It cannot be elevated sufficiently to remove it or to permit unauthorized entry. In such position the arrangement is that which would be suitable for a lower floor storm and screen window assembly.

When the lower window is reversed end for end, as shown in Fig. 6, with bottom rail of the lower window seated within the channel 46 of the upper sash the screen then is in position, as shown in such Fig. 6, to be raised or lowered as desired. This arrangement might be suitable for an upper floor storm window assembly where it might be desired to elevate the screen to shake a dust mop or the like.

It will be seen that when the sashes are arranged as shown in Figs. 5 and 6, a seal tight joint is formed between the top rail of the screen and the lower rail of the upper sash.

When the sashes are arranged, as shown in Fig. 2, the lower sash can be readily elevated out of its channel 32. The upper sash may be then lifted within the header sufficiently to clear the top of the screen and permit the bottom of the upper sash to be pulled inwardly laterally and said sash lowered out of the header. The screen may then be readily lifted out of its channel. When the sash elements are arranged, as shown in Fig. 6, the screen may be raised out of its channel 32. The lower sash may be lifted up into the header out of the channel 46 of the bottom rail of the upper sash and may be withdrawn laterally inwardly being lowered out of the header at the same time. The upper sash may then be dropped and withdrawn inwardly.

When the sash elements are arranged, as shown in Fig. 5, it will be apparent that the screen cannot be lifted except a small distance because the top rail of the screen will engage the channel 52 thereabove of the lower sash. The lower sash may, however, be dropped sufficiently to disengage its top rail from the header and thereby permit its withdrawal inwardly laterally. After it has been removed the screen may be readily lifted out of its channels and the upper sash may be removed.

When the screen is arranged as shown in Fig. 5 or 6 and the upper sash U and lower sash L are arranged side by side in the upper half of the window frame as illustrated, the bottom of the channel 46 of the upper sash rests upon the upper end of the outer side wall of the lower inner guide channel 32. Figs. 5 and 6 show the top rail of the screen bearing snugly against the inner side wall of the channel 46 of the upper sash U. It is apparent, therefore, that the outer side wall of the channel 32 must support this upper sash.

There is sufficient flexibility in the assembly to permit assembly and disassembly to be carried out.

What I claim is:

1. In a window assembly, opposed jamb members the lower halves of which define two complementary opposed pairs of lower guide channels, the two side walls of the complementary inner guide channels terminating at the top within the lower halves of the jamb members and adapted to receive a screen sash therein, the outer side walls of the complementary inner guide channels constituting the inner side walls of the complementary outer guide channels, the outer side walls of the complementary outer guide channels extending throughout the upper halves and lower halves of the jamb members, a header extending between the jamb members and defining a pair of downwardly open channels one surmounting the complementary inner guide channels and the other surmounting the complementary outer guide channels, a lower window sash slidably mounted between the jamb members within the outer complementary pair of lower guide channels, an upper window sash mounted between the upper halves of the jamb members adjacent the extended outer side walls of the complementary outer guide channels and having a lower rail defining a downwardly open channel adapted to receive the upper rail of a sash disposed therebelow, the header channels having a depth greater than the depth of the channel of the lower rail of the said upper sash.

2. In a window assembly, opposed jamb members provided with two opposed complementary pairs of sash guide channels defined by three parallel spaced apart guide channel walls extending throughout the lower halves only of the jamb members, each of said jamb members provided throughout its upper half with only one guide channel wall which is a continuation of the outer wall of the outer guide channel of the lower half of the jamb member, the other two guide channel walls of the lower halves of the jamb members terminating at their upper ends below the upper halves of the jamb members, a header extending between said jamb members and provided with two downwardly open header channels surmounting and in line with the two guide channels of the lower halves of the jamb members, a sash element mounted between the lower halves of the jamb members within the two outer complementary guide channels, a sash element mounted between the upper halves of the jamb members and resting against the guide channel walls of said upper halves and surmounting the sash element disposed within the outer guide channels of the lower halves of the jamb members, said upper sash element having its top rail received within the header channel thereabove and its bottom rail provided with an outer flange adapted to overlap the outer side of

the top rail of the sash element therebelow when the upper sash seats upon said lower sash element, the distance between the top rail of the upper sash and the bottom of the header channel within which it is mounted being greater when the upper sash is seated upon said lower sash element than the vertical width of said outer flange of the lower rail of the upper sash.

5 3. In a window assembly, opposed jamb members the lower halves of which are provided with two complementary opposed pairs of lower guide channels defined by three parallel spaced apart guide channel walls, the outer side walls of the outer pair of lower guide channels being extended throughout the upper halves of the jamb members, the two other guide channel walls terminating at their upper ends below the upper halves of the jamb members, a header extending between the jamb members and defining two downwardly open channels one adjacent to said outer guide channel walls, a lower sash element mounted between the lower halves of the jamb members within the outer guide channels, an upper sash element mounted between the upper halves 10 20 25 30 35 40 45 50 55 60 of the jamb members surmounting the lower sash element and received at the top within the header channel, said upper sash element having a bottom rail provided with a downwardly open channel adapted to receive the top rail of the sash element therebelow, said bottom rail further provided with an upwardly open channel offset inwardly said downwardly open channel sufficiently to surmount the outer walls of the inner lower guide channels, said upwardly open channel having an inner wall adapted to bear against the top rail of a sash element mounted within the inner lower guide channels which top rail is disposed above the upper ends of the outer walls of the inner lower guide channel.

4. A window assembly as defined in claim numbered 2 characterized in that the bottom rail of said upper sash element is also provided with a flange portion projecting inwardly substantially normal to said bottom rail sufficiently to surmount the upper ends of the intermediate guide channel walls of the lower halves of the jamb members when the upper sash is in the elevated position.
